(74) *Attorney, Agent, or Firm* — Donald J. Lecher; BUTZEL LONG

(57) **CLAIM**

The ornamental design for a wall rack as shown and described.

DESCRIPTION

FIG. 1 is a top, front, right side perspective view of a wall rack showing our new design;

FIG. 2 is a bottom, front, left side perspective view thereof;

FIG. 3 is a top, rear, right side perspective view thereof;

FIG. 4 is a bottom, rear, left side perspective view thereof;

FIG. 5 is a front elevation view thereof;

FIG. 6 is a rear elevation view thereof;

FIG. 7 is a left elevation view thereof;

FIG. 8 is a right elevation view thereof;

FIG. 9 is a top plan view thereof;

FIG. 10 is a bottom plan view thereof; and,

FIG. 11 is a partially assembled top, front, right side perspective view thereof.

The broken lines show portions of the wall rack that form no part of the claimed design. Dash-dot lines indicate enclosed boundary areas which form no part of the claimed design.

1 Claim, 10 Drawing Sheets
